UNITED STATES PATENT OFFICE.

REISSUED

THEODORE W. BEAN, OF NORRISTOWN, PENNSYLVANIA.

MACHINE FOR ROLLING CAR-WHEELS.

SPECIFICATION forming part of Letters Patent No. 361,479, dated April 19, 1887.

Application filed April 26, 1886. Serial No. 200,237. (No model.)

To all whom it may concern:

Be it known that I, THEODORE W. BEAN, a citizen of the United States, residing at Norristown, in the county of Montgomery and State of Pennsylvania, have invented certain new and useful Improvements in Rolling-Mills used in the Manufacture of Steel Car-Wheels, of which the following is a specification.

The purpose of my invention is to produce car-wheels of rolled and compressed steel, and I attain this object by means of rolls, as shown in the accompanying drawings, forming part of this application, and in which similar letters of reference indicate like parts.

15 Figure 1 shows a side view of the rolls and bearing.

F and G are two roll-heads, so shaped as to give the desired form to the steel ingot which is to be compressed by them into the exact size 20 required.

H is another roll, whose periphery gives the shape to the tread of the wheel. It will be readily noticed that it moves by friction with the ingot, and is not actuated by either of the 25 side rolls. The shafts P and R carry the roll-heads and the large gear-wheels, which engage one another directly. I and J are the said beveled gear-wheels.

A and B are housings in which the shafts P 30 and R are journaled. The ball-box K in the upper bearing, B, supports the extreme end of the shaft P, and its construction allows the roll-head at the other end to be raised or lowered while the bearing acts as a stationary 35 pivot. The desired pressure on the roll-head F is given by means of the screw E on the rider N and allows the roll-heads to be separated sufficiently while the steel ingot is being placed between them on the table M.

40 S and C are suitable projections on the housing A, in which the horizontal roll H is journaled.

Fig. 2 shows a front view of the housings without the rolls F and G. Fig. 3 shows the 45 housings B; Fig. 4, the arm C and the bearings S for the roll H.

Power is applied to the shaft R. The ingot of steel having been cast to a suitable shape and sufficiently heated is placed in position on 50 the tube M between the roll-heads. The screw E forces the rider N onto the roll F, and the

steel ingot is pressed between it and the lower roll. The rolls H and G act as a die, while the upper roll gradually descends and compresses the metal, rendering it homogeneous throughout and of greater tensile strength.

I do not limit myself to two rolls for shaping the sides of the car-wheel, as it is evident that three or more may be geared directly together.

60 I am aware that mills for rolling iron car-wheels have been patented before this application was made; but their construction differs materially in important details, and especially in the gearing of the two shafts. The ball-bearing allowing of the rocking of the shaft carrying one of the rolls is, as far as I am aware, also novel.

Having now fully described my said invention, what I claim, and desire to protect by Letters Patent, is—

1. In a mill for rolling steel car-wheels, the combination, with a sliding bearing and a ball or rocking bearing, of the shaft of one of the rolls journaled in said bearings and carrying 75 a beveled gear-wheel placed between said bearings and engaging directly with the gearing on the shaft of the other roll, substantially as described.

2. In a mill for rolling car-wheels, the combination, with two or more roll-heads of suitable shape to form the sides of the car-wheel, of their shafts carrying beveled gear-wheels directly engaging one another and situated between sliding and rocking bearings, substantially as described.

3. In a mill for rolling car-wheels, the combination, with a horizontal roll for shaping the face of the wheel journaled in stationary bearings, of two or more roll-heads of suitable 90 shape to form the sides of the car-wheel, and their shafts, each carrying a beveled gear engaging the other gear directly, each journaled on one side of the said gear in sliding bearings situated near the roll-heads controlled by 95 set-screws, and on the other in rocking bearings, substantially as described.

THEODORE W. BEAN.
